United States Patent Office.

MILTON L. DRAKE, OF ROCKFORD, ILLINOIS.

Letters Patent No. 96,210, dated October 26, 1869.

IMPROVED SHAFT AND COUPLING-SHIELD.

The Schedule referred to in these Letters Patent and making part of the same.

To all whom it may concern:

Be it known that I, MILTON L. DRAKE, of Rockford, in the county of Winnebago, and State of Illinois, have invented a new and improved Shaft and Coupling-Shield; and I do hereby declare that the following is a full and exact description of the same, referring being had to the accompanying drawings, and to the letters of reference marked thereon.

This invention has for its object the covering of shafts and couplings in such manner as to make it impossible for the persons of the operators or others to come into contact with them, and thereby receive injury; and, to that end,

It consists in shields of peculiar construction, which are adapted to cover the couplings, and a tubular box, adapted to cover the shafting.

In the drawings—

Figure 1 is a plan view of my invention;

Figure 2 an end view of one form of the shield;

Figure 3 a similar view of another form of the same; and

Figure 4, a section through line x in fig. 1.

To enable others skilled in the art to make and use my invention, I will now proceed to fully describe its construction and operation.

A represents a box of any proper form and length, which is provided with a tubular bore, as indicated in the drawings.

B represents a shield, which is provided with straight

ends and sides, but curving top, the ends having the square opening b, which corresponds in size with the box A.

C also represents a shield, which is constructed much like the shield B, but is double, the parts being hinged at c, as shown, and held together by hooks at c', when in position.

The shield B is intended especially for use when the coupling lies so near the ground that there is not room enough to cover the lower side of it. Of course, in such cases, it is not necessary to do so.

The shield C is intended for use about the coupling when it is elevated so high that all its circumference is exposed.

These shields are easily removed when it is necessary to get at the couplings or shafts. They can be cheaply constructed and easily applied.

Having thus fully described my invention, What I claim as new, and desire to secure by Letters Patent, is—

The box A, shield B, box D, and shield C, with hinge c and hook c', when combined and arranged as described for the purpose set forth.

This specification signed and witnessed, this 27th day of August, 1869.

MILTON L. DRAKE.
